(57) **CLAIM**

The ornamental design for a dental material applicator with partitioned packaging as shown and described.

DESCRIPTION

FIG. 1 is a top, left, rear perspective view showing a new design for a dental material applicator with partitioned packaging;

FIG. 2 is a top plan view thereof;

FIG. 3 is a bottom plan view thereof;

FIG. 4 is a right-side elevation view thereof;

FIG. 5 is a left-side elevation view thereof;

FIG. 6 is a front view elevation thereof;

FIG. 7 is a rear view elevation thereof; and,

FIG. 8 is bottom, right, rear perspective view thereof.

The broken lines in the drawings depict portions of the dental material applicator with partitioned packaging that form no part of the claimed design.

1 Claim, 5 Drawing Sheets
